UNITED STATES PATENT OFFICE.

ALBERT T. RATLIFF, OF HATTIESBURG, MISSISSIPPI, ASSIGNOR TO FREE STUMP REMOVER MANUFACTURING COMPANY, OF LAUREL, MISSISSIPPI, A CORPORATION OF MISSISSIPPI.

PROCESS OF AND APPARATUS FOR REDUCING STUMPS.

1,190,006.

Specification of Letters Patent.

Patented July 4, 1916.

Application filed June 11, 1915. Serial No. 33,595.

To all whom it may concern:

Be it known that I, ALBERT T. RATLIFF, a citizen of the United States, residing at Hattiesburg, in the county of Forrest and 5 State of Mississippi, have invented certain new and useful Improvements in Processes of and Apparatus for Reducing Stumps; and I do hereby declare the following to be 10 a full, clear, and exact description of the invention, such as will enable others skilled in the art to which it appertains to make and use the same.

This invention relates to processes of an apparatus for reducing stumps, and one of 15 the principal objects of the invention is to provide a retort for inclosing the stump, and an outer casing and an intermediate hood adapted to receive fuel for heating the retort, and said retort being connected to 20 an outlet pipe leading to a still or worm, so that the products and by-products from the stump may be obtained, and the stump may be reduced to charcoal.

Another object of the invention is to provide a process for obtaining charcoal, a non-condensable gas, light oils containing crude turpentine, tar and pyroligneous acid, all of which may be separated into various commercial products by redistillation.

30 The foregoing and other objects may be attained by means of the construction illustrated in the accompanying drawings, and the process to be described in relation thereto.

In the accompanying drawings: Figure 1 is a vertical sectional view of a portable apparatus for carrying out the process referred to, said apparatus being of the type known as natural draft apparatus. Fig. 2 is a view in partial vertical section and partial elevation of a forced draft apparatus, showing the fan blower and its connection with the apparatus in elevation. Fig. 3 is a vertical sectional view of a still further modified form of apparatus, and Fig. 4 is a sectional view taken on the line 4—4 of Fig. 3 looking in the direction indicated by the arrows.

Referring to the drawings, the numeral 1 designates the outer casing of the apparatus which is adapted to rest on the ground, and is provided with a draft opening 2 at the upper end thereof to admit air. A hood 3 is supported by means of metal brackets 4 connected at one of their ends to the inner

wall of the casing 1, and at their other ends connected to the outer wall of the hood 3 by a bolt 5. The hood 3 at its upper end is provided with a smoke stack 6 having a damper 7 therein. A retort 8 having its lower end provided with an annular flange adapted to rest upon the ground and surround and inclose a pine stump *a*, is connected to the hood 3 by metal brackets or spacers 10. Supporting members 11 are connected to the lower edge of the hood 3 at their upper ends and their lower ends are bolted to the flange 9 of the retort 8. Leading from the top of the retort 8 is an outlet pipe 12 which leads into a still casing 13, and connects with a coil or worm 14. The casing 13 is mounted on a truck 15, and all 70 of the apparatus may be readily moved from place to place. The condenser coil or worm 14 has an outlet 16 in the bottom of the casing 13 and a receptacle 17 may be disposed immediately under the outlet. 75

An inlet pipe 18 for the cooling fluid or liquid and an outlet pipe 19 are connected to the casing 13. The pipe 12 may be provided with a removable coupling 20 to permit the pipe 12 to be removed from the condenser 80 when it is desired to move the apparatus from one stump to another.

Referring to Fig. 2 of the drawing, the apparatus is substantially the same as that shown in Fig. 1, excepting that there is a forced draft appliance used comprising a fan blower 21 communicating by means of the pipe 22 with the upper end of the outer casing 1.

As shown in Fig. 3, the outer casing 23 is provided with an air inlet pipe 24, a smoke stack 25 and a damper 26. The retort 27 extends below the lower end of the casing 23, and supported upon the retort by suitable brackets 28 is the hood 29, said retort 95 having a removable cap or cover 30 connected thereto by means of pivoted bolts 31 adapted to engage recesses in the flange of the cap or top 30. It is to be understood that this casing may be provided with a door 36 through which to feed fuel, so that the heat on the exterior of the retort may be maintained as long as it is necessary to properly reduce the stump.

Intake pipes 32 having their lower ends 105 open, and provided with horizontal branches

33 are connected to an elbow 34 to which the outlet pipe 35 is attached, said pipe 35 leading to a condenser.

The operation of the invention may be briefly described as follows:

The retort 8 as shown in Figs. 1 and 2 or 27 as shown in Fig. 3 is placed over the stump *a* and a fire or any other suitable heating means is placed within the outer 10 casing at the base of and around the retort. Air to support the combustion, as shown in Fig. 1, enters the casing at the inlet 2, and is carried up around the retort inside the hood 3, thus raising the temperature to a high 15 degree and reducing the stump *a* to charcoal, and carrying off the by-products through the pipe 12 to the condenser coil, and out 20 into the receptacle 17. The arrows in the various figures show the direction of the draft.

From the foregoing it will be obvious that the apparatus can be readily removed from one stump to another, and as shown in Fig. 3, the cap or cover 30 may be removed if desired for the purpose of permitting the introduction of roots, fat pine, or other matter to be reduced.

Various changes may be made in the details of construction without departing from 30 the spirit and scope of the invention as defined in the claims.

What is claimed is:—

1. An apparatus for reducing stumps and obtaining the by-products therefrom consisting of a retort, having a pipe leading to a condenser coil, a casing surrounding the retort, and a hood supported upon the retort, means for admitting air to support com- 35

bustion between the retort and the outer casing.

2. An apparatus of the character described comprising a casing, a retort within the casing, a hood connected to the retort, and draft appliances to support combustion between the outer casing and the retort, and 45 an outlet pipe leading from the retort to a condenser coil.

3. An apparatus of the character described comprising a casing, a retort within the casing, an outlet pipe leading from the 50 top of the retort to a condenser coil, an outer casing, a hood between the retort and outer casing, and a forced draft device for supporting combustion between the outer casing and the retort.

4. An apparatus for reducing pine stumps comprising an outer casing, a retort within the outer casing, a hood disposed between the retort and outer casing, a smoke stack, an inlet opening for air, an outlet pipe for 60 the retort, a condenser coil to which the outlet pipe is connected, and means to force air into apparatus.

5. The herein described process of destroying a stump in the ground and gathering 65 its by-products, consisting in placing a retort over the stump, applying heat to the exterior of the retort to reduce the stump, and conveying the vapors generated in the retort to a condenser.

In testimony whereof I affix my signature in presence of two witnesses.

ALBERT T. RATLIFF.

Witnesses:

M. GALBRAITH,
H. S. ARRINGTON.
